UNITED STATES PATENT OFFICE.

GEORGE W. HOYT, OF CHICAGO, ILLINOIS.

DESIGN FOR A STOCKING-SUPPORTER CLASP.

SPECIFICATION forming part of Design No. 21,090, dated September 29, 1891.

Application filed June 26, 1891. Serial No. 397,653. Term of patent 14 years.

To all whom it may concern:

Be it known that I, GEORGE W. HOYT, a citizen of the United States, residing in Chicago, in the county of Cook and State of Illinois, have invented a new and useful Design for Stocking-Supporter Clasps, of which the following is a specification.

Figure 1 of the drawings shows a plan of the clasp of a stocking-supporter embodying my design, and Fig. 2 is an enlarged section thereof on the line 2 2 of Fig. 1.

My design consists in a clasp for stocking-supporters, having a bead formed along the outer edge and extending around the lower end and up the sides to a point about opposite the vertical center of the opening in the clasp.

In the drawings, *a a* represent the cross-bars at the top of the clasp. *b b* are the vertical sides of the clasp, which extend downward from the bars *a* in converging lines for a part of their length, then in

substantially parallel lines for a farther distance, and unite at the bottom *c*, thus forming a heart-shaped opening *d*. That portion 25 of the sides below the plane of the vertical center of the opening *d* is provided along the outer edge with a raised bead *e*, the construction being clearly shown in the section given at Fig. 2, that portion of the metal adjoining 30 the bead being reduced in thickness, so as to make the bead prominent.

I claim--

The design for a stocking-supporter, having the raised bead *e* extending around the outer 35 edge of the sides *b* of the opening *d* and having the extremity vanishing in the body portion of the stocking-supporter in proximity to the cross-bar *a*, substantially as shown and described.

GEORGE W. HOYT.
